UNITED STATES PATENT OFFICE.

JONAS HINKLEY, OF NORWALK, OHIO, ASSIGNOR TO THE HINKLEY
KNITTING MACHINE COMPANY, OF BATH, MAINE.

IMPROVEMENT IN KNITTING-MACHINE.

Specification forming part of Letters Patent No. 101,875, dated April 12, 1870.

To all whom it may concern:

Be it known that I, JONAS HINKLEY, of Norwalk, in the county of Huron and State of Ohio, have invented a new and useful Improved Knitting-Machine; and I do hereby declare the following to be a full, clear, and exact description thereof, which will enable others to make and use my invention, reference being had to the accompanying drawings, forming part of this specification, in which—

Plate 1 shows a front elevation of my machine. Plate 2 is an end elevation. Plate 3 is a top plan and view.

Plate 4 shows the following details: Figure 1, the wheel that imparts intermittent motion to the rack and comb, and operates the needle-looper, the needle being shown in two positions. Fig. 2 illustrates the method of disconnecting the needle from the wheel. Fig. 3 is an enlarged detail edge view of the wheel, and illustrates the manner in which it moves the rack. Fig. 4 is a bottom view of the needle as threaded. Fig. 5 is a view of parts of the looper.

Plate 5 shows the following details: Fig. 1 is a vertical transverse section of the expanding disks which work in or engage with the driving-wheel. Fig. 2 is an end view of the rack and comb. Fig. 3 is a top view of the arm that moves the index-plate which shows the number of times the rack and comb traverse. Fig. 4 is a view of a part of one of the devices to regulate the narrowing or widening of the work or fabric. Fig. 5 is a detail of the thread-regulating or tension device. Fig. 6 shows the order, connection, and character of the stitches.

Letters Patent of the United States were granted to me on the 29th day of May, A. D. 1866, for an improved knitting-machine.

In the following specification it has been found necessary to describe and represent sundry of the parts, if not most, of the said machine, in order to fully show the application of my present improvements. I therefore desire it to be understood that I do not herein claim any of the features, devices, or combinations as set forth and described in such patent, but limit my present invention to the principles or combinations as defined

in the claims at the latter part of this my specification, such claims to which reference may be had serving to exhibit the nature of my present invention.

The first part of my invention relates to the combination of the cone and loop-forming devices with the wheel F, hereinafter mentioned, and employed for operating the comb and other parts applied to such wheel.

Another part of my invention relates to the combination of the eye-pointed needle, the vibratory looping-hook, and the comb, the looper or looping mechanism operating to take the loop from the needle and deliver and transfer it to a tooth of the comb, substantially as hereinafter explained.

Another part of my invention consists in combining, with the sleeve of the needle-carrying arm and its pin, a collar, bolt, and spring, as hereinafter explained.

Another part of my invention consists in the slide G, constructed as hereinafter described.

Another part of my invention consists in constructing the comb with upwardly-turned teeth, as and for the purpose hereinafter set forth.

Finally, my invention further consists in a knitting machine composed of all the devices or instrumentalities shown in the accompanying drawings, and hereinafter described, when constructed, combined, and used substantially in the manner and for the purposes as specified.

Having thus premised, I will now proceed to explain the machine and the parts thereof which I consider as new and of my invention.

Motion is imparted to my machine by a drive-wheel, B, revolved by any convenient means. This wheel has a groove on its periphery to receive an expansible wheel or friction-gear, E, rigidly set upon the horizontal shaft D. This shaft D also carries the wheel F, which moves the rack, needle, and looper, and also, in connection with the slides G G', reverses the motion of the rack when desired, and as arranged by the operator.

A denotes the base or platform of my machine.

The shaft D is supported upon proper standards, one of which, I, also holds suspended at

one side of the wheel F both the needle and looper, arranged in their respective carriers. These carriers are attached to sleeves through which pass supporting bolts or journals, which bolts are attached or secured to the standard or support I in such a manner as to allow of the free vibratory motion of both looper and needle.

h shows the sleeve to which the arm or carrier of the looper is attached; *i*, that of the needle-carrier.

The carrier or arm of the needle is slotted, as indicated at *v* in Fig. 1, Plate 4, and the stud or eccentric *x*, same figure and plate, works in the said slot. Thus, by the revolution of the wheel F a vibratory reciprocating motion is imparted to the carrier *v'*, and consequently to the needle. The path or cam-groove *y* on the same face of the wheel F, (see same figure and plate,) imparts a similar motion to the looper and its carrier *u* by means of the stud *z* working in the said groove or cam.

Upon the periphery of the wheel F, Plate 4, Fig. 3, is placed a projecting edge, *r*, fixed to the said periphery. The part or "fin" *r'* thereof is movable, and slides a short distance from one to the other side by the turning of the small movable crank or lever *w'*. When the movable part or fin *r'* of the edge is thus turned to one or the other side by the crank *w'*, the said edge forms a slow screw or helix in one revolution of the wheel F, so that as F revolves the said free end or fin *r'* of the edge *r* at each revolution enters a space of the rack *a*, Plate 1, one space or tooth in advance of that one in which the fixed part *r* of the said edge is traveling, thus advancing the rack *a* at each revolution of the wheel F a distance equal to the space occupied by one of the teeth of the said rack. Thus the motion of the rack and comb is obtained.

Set upon the plate, on the edge of which is formed the comb *c*, Plate 1, are two slides or dogs, *G G'*. These are held in position by having on their bottoms, on the sides contiguous to the front side of the rack *a'*, lips and grooves which overlap a similar lip, and fit into a similar groove on the said rack. (See *G*, Plate 2.) Through the hollow cylinder *e'* of these slides *G G'* passes a rod bifurcated at its end 12, (see Fig. 4, Plate 5,) which points or bifurcations fit into the spaces between the teeth of the rack *a*. Around this rod is coiled a spring, 11. The rod is turned by a thumb-piece, *e''*, on the front end thereof, and on the inner face of this thumb-piece are small projections *a⁵*, which fit into corresponding recesses *b⁵*, (see Figs. 3 and 4, Plate 5,) in the outer or front ends of the cylinders *e'*. When the said projections thus sink into the said recesses, the points or bifurcations of the rod are held firmly in the spaces between the teeth of the rack; but when, by the turning of the thumb-piece, the said projections are thrown out of the said recesses, and the rod revolved, the points or bifurcations are moved or drawn

backward somewhat into the cylinder *e'* and partially out of the said spaces. Thus as the rod is turned, these bifurcations or points, by alternately passing into the spaces in the rack, operate as a pinion to move the slides *G G'* along the rack, and on the metal plate or sheet on which the comb is formed, in either of two directions, as the said rod may be turned.

The coiled spring 11 is so arranged around the rod and inside of the cylinder *e'* as to keep the forked or bifurcated portion of said rod in contact with the rack *a*, but admits of the said rod being withdrawn or pulled out of the cylinder sufficiently to disconnect the rod entirely from the rack, and thus allow the slide *G* to be moved freely along the comb-plate.

When the thumb-piece *e''* is turned in the ordinary manner, the projections on its inner surface, by being alternately forced out of and falling into their corresponding recesses, serve to indicate to the operator the distance which the slide *G* is moved. They also prevent the working of the machine from turning the rod, thus serving also to keep the slide in any desired position on the plate. The distance between the two slides indicates the width of the work or fabric. These two slides or carriages *G G'* are somewhat different in form, and subserve somewhat different purposes. This will be best understood by reference to *G*, Plate 3, where there are seen on the face of the said slide, toward the rack *a*, two inclined faces or surfaces and a projection, *s'*, and to *G'*, same plate, where there is exhibited the projecting arm *s*.

By means of the two projections *s s'* the reverse motion of the rack is obtained, and in the following manner: When, by the motion of the rack *a*, either slide is approaching the wheel F, the movable part or fin *r'* of the edge of said wheel is found to be turned toward the said approaching slide or carriage, and when the said carriage has approached sufficiently near to the said wheel F to enable the projecting parts *s* or *s'*, as the case may be, to touch the wheel, one of these points *s* or *s'* comes in contact with the crank or lever *w'*, by which the movable edge *r'* is moved, and thus presses the said movable edge to the other side of the periphery of the wheel, thereby causing it to engage the spaces of the rack *a* on the said other side of the wheel F, and thus reverse the motion of the said rack. Therefore it will be seen that the rack traverses only the distance between the said slides or carriages *G G'*, and hence they indicate the width of the work to be performed, successive rows of stitches being added to the work by each traverse of the rack *a*.

The two inclined faces of the carriage or slide *G* operate the recording-disk, by which the number of the successive rows of stitches added to the work is indicated.

M is this disk, set and turning in a horizontal plane on an upright spindle, *l*. The pe-

the needle and deliver or transfer it to a tooth of the comb, substantially as set forth and specified.

4. In combination with the sleeve of the needle-carrying arm and its pin, the collar, bolt, and spring, for retaining the needle-arm in connection with or allowing it to be moved away from its operating devices.

5. The slide G, having the mechanism described for changing its position on the comb, and also the projection for operating the arm 4 which moves the recording-disk, all substantially as described.

6. A knitting-machine comb, having the

upwardly-curved or inclined teeth, the whole being as and for the purpose shown and hereinbefore explained.

7. A knitting-machine composed of all the devices and instrumentalities shown in the accompanying drawings and herein described, when constructed, combined, and used substantially in the manner and for the purposes specified.

JONAS HINKLEY.
